UNITED STATES PATENT OFFICE.

HELLEN P. HADLEY, OF BOSTON, MASSACHUSETTS.

DESIGN FOR A RUG.

45,713.

Specification for Design.

Patented May 5, 1914.

Application filed November 19, 1913. Serial No. 801,998. Term of patent 14 years.

To all whom it may concern:

Be it known that I, HELLEN P. HADLEY, a citizen of the United States, residing at Boston, in the county of Suffolk and State of Massachusetts, have invented a new, original, and ornamental Design for a Rug, of which the following is a specification, reference being had to the accompanying drawing, forming a part thereof.

The figure is a plan view of a rug showing my new design.

I claim:

The ornamental design for a rug, as shown.

In testimony whereof I have hereunto set my hand in presence of two subscribing witnesses.

HELLEN P. HADLEY.

Witnesses:

CHARLES S. GOODING,
SYDNEY E. TAFT.
